UNITED STATES PATENT OFFICE.

STANLEY W. NICHOLSON, OF TOLEDO, OHIO, ASSIGNOR, BY MESNE ASSIGNMENTS, TO
THE DURA COMPANY, OF TOLEDO, OHIO, A CORPORATION OF OHIO.

WINDOW REGULATOR.

Application filed March 8, 1926. Serial No. 93,250.

The invention relates to window regulators and refers more particularly to the assembly including the crank and irreversible drive mechanism. One of the objects 5 of the invention is to provide a permanently inclosed assembly of the parts forming the irreversible drive mechanism. Another object is to provide an improved assembly of crank and drive shaft. A further object is 10 to make use of the escutcheon to support one end of the drive shaft.

With these as well as other objects in view the invention resides in the novel features of construction and combinations and arrangements of parts as more fully herein- 15 after set forth.

In the drawings:-

Figure 1 is an interior side elevation, partly broken away, of a vehicle door having applied thereto a window regulator embodying my invention;

Figure 2 is an enlarged cross section through the assembly, including crank and irreversible drive mechanism;

Figures 3, 4 and 5 are cross sections, respectively, on the lines 3—3, 4—4 and 5—5 of Figure 2;

Figure 6 is a view corresponding to Figure 2 and showing a modification;

Figure 7 is a cross section on the line 7—7 of Figure 6;

Figure 8 is an elevation of a portion of Figure 6.

As shown in the present instance, the window regulator embodying my invention is 35 adapted to raise and lower the window 1 slidable in the frame 2 of a vehicle door from a position closing the opening in the upper portion of this door and into the 40 chamber in the lower portion. The window regulator, as shown, has the pivotal lifter arm 3, which is connected at its outer end to the window and pivotally mounted upon the outer frame at its inner end. 4 is a rack 45 pivotally connected at its lower end to the lifter arm 3 and meshing with the pinion 5 which is driven through suitable irreversible drive mechanism.

The pinion, crank and irreversible drive mechanism are mounted as a unit upon the 50 lock board 7 of the door, the pinion being located at the outer side of the lock board and the crank at the inner side. The pinion is secured to the cup-shaped driven member 7 of the irreversible drive mechanism and 55 the crank is secured to the drive shaft 8 forming the driving member of the irreversible drive mechanism. This drive shaft is in the nature of a flat bar and may be mill stock. 9 is the sleeve extending through the 60 lock board and having bearing faces for the opposite ends of the driven member 7 and providing a chamber surrounding the driven member for receiving the coil spring 10. The driven member is provided with the 65 longitudinally extending slot 11 formed between the inwardly depressed circumferentially spaced tongues 12 and the spring has inturned ends 13 extending into this slot. The drive shaft 8 also extends through the 70 slot between the inturned ends of the spring and has secured to its outer end the flanged washer 14 which is journaled within the driven member 7. The sleeve is rigidly secured to the lock board by suitable means including the spring washer 15 and the nut 16 threaded upon the outer end of the sleeve and the radially outwardly extending flange 17 at the inner end of the sleeve. 75 With the arrangement as thus far described, 80 the drive shaft 8 is adapted to contact with one of the inturned ends of the spring to contract this spring and to drive through this inturned end the driven member 7 of the irreversible drive mechanism, thereby rotating the pinion 5. However, with power removed from the drive shaft and power applied to the pinion to rotate the same, this pinion, through the driven member 7, coming into contact with one of the inturned 85 ends of the spring will expand the latter to firmly frictionally engage the sleeve 9 and thereby prevent rotation of the pinion.

For the purpose of supporting the inner end of the drive shaft 8, I make use of the 90 escutcheon 18 which, as shown, has its outer

- end extending around the free outer edge of the radial flange 17 of the sleeve and permanently secured thereto as by solder. This escutcheon has its inner end extending around the outer cylindrical edge of the washer 19, which is rigidly secured to the drive shaft. The washer 19 is then rotatably mounted upon the escutcheon and consequently the inner end of the drive shaft 5 is rotatably supported by the escutcheon. Furthermore, this escutcheon additionally serves with the sleeve 9 to permanently inclose the irreversible drive mechanism.
- To secure the drive shaft to the crank, I have formed upon the inner end of the drive shaft and integral therewith the transverse arm 20 and have formed in the arm 21 of the crank the longitudinally extending slot 22 of a size to receive this transverse arm. The 10 crank arm and the transverse arm of the drive shaft are secured to each other by means of the pin 23 which extends transversely through these two arms and is located in the inner side portion 24 of the 15 crank arm which is of greater width than the outer side portion.
- The modification shown in Figures 6, 7 and 8 has the same general arrangement of parts with the exception that the drive shaft 25 is formed of round stock and has the swaged tongue 26 which extends outwardly through the longitudinally extending slot 27 formed in the cup-shaped driven member 28 of the irreversible drive mechanism.
- Also in this modification the sleeve 30, which extends through and is rigidly secured to the lock board 31, has at its outer end the inturned radial flange 32 forming a bearing for the reduced outer end 33 of the 30 driven member. 34 is the pinion formed integral with the driven member and located within and housed by the sleeve, which latter is provided with the peripheral slot 35 registering with the pinion and providing 35 for the passage of the rack to mesh with the pinion.
- From the above description it will be seen that I have provided a permanently inclosed assembly of irreversible drive mechanism; that I make use of the escutcheon to support the inner end of the drive shaft; and that I have provided an improved means for securing the drive shaft to the crank.
- What I claim as my invention is:
1. The combination with a sleeve, of a tubular member within said sleeve provided with a longitudinally extending slot, a member secured to and driven from said tubular member, a crank and a flat bar connected 55 to said crank and extending within and rotatably engaging said tubular member, said bar having a portion extending within the slot of said tubular member and a coil spring surrounding said tubular member and arranged within said sleeve, said spring 60 having inturned ends extending into the slot of said tubular member and on opposite sides of said flat bar.
2. The combination with a support, of a rotatable drive shaft, a crank connected to 70 said shaft and an escutcheon secured to said support and rotatably supporting said shaft at a point adjacent to said crank.
3. The combination with irreversible drive mechanism including a drive shaft, a driven 75 member, a coiled member surrounding said driven member and having inturned ends engageable with said driven member and shaft and a sleeve surrounding said coiled member, of an escutcheon rigidly secured to said 80 sleeve and forming a support beyond said sleeve for said shaft.
4. The combination with a sleeve, of a driven member within said sleeve having a tubular portion provided with a longitudinally 85 extending slot, a crank and a drive shaft connected to said crank and extending within and rotatably engaging said tubular portion, said crank having a swaged projection extending within the slot of said tubular 90 portion and a coil spring surrounding said driven member and arranged within said sleeve, said spring having inturned ends extending into the slot of said tubular portion and on opposite sides of said projection.
5. The combination with a drive shaft and a driven member, of an irreversible drive mechanism between said shaft and member, and means for permanently housing said 100 mechanism comprising a sleeve surrounding said mechanism and having a reduced end portion forming a bearing for said driven member, and an escutcheon secured to said sleeve and forming a support for said drive 105 shaft.
6. The combination with a support having an opening therein, of a drive shaft and a driven member, a sleeve in said opening surrounding said shaft and driven member and having a reduced end portion forming a bearing for said driven member, a radial flange extending from the other end of said sleeve, a washer on the reduced end portion of said sleeve, and means carried by the 110 reduced end of said sleeve for forcing said flange and washer into clamping engagement with the opposite walls of said support for rigidly securing the sleeve in said opening.
7. The combination with a sleeve, of a 120 driven member within said sleeve, a drive shaft comprising a flat bar extending within and rotatably engaging said driven member, a coil member surrounding said driven member and having inturned ends engageable 125 with said driven member and bar, a transverse arm extending from the outer end of said bar, a crank for driving said bar having an arm provided with a slot for receiving said transverse arm, and means extending 130

through said arms for securing the same to each other.

8. The combination with a drive shaft and a driven member, of an irreversible drive mechanism between said shaft and member, and means for permanently housing said mechanism comprising a sleeve surrounding said mechanism and having a reduced end portion forming a bearing for said driven

member, an escutcheon secured to said sleeve and having its outer end provided with an open return bent portion, and a cup-shaped washer secured to said drive shaft and having its rim rotatably engaging the return bent portion of said escutcheon. 10

In testimony whereof I affix my signature. 15

STANLEY W. NICHOLSON.
